14 Claims

This invention relates to an electronic digital information processor and, more particularly, to apparatus for performing sub-word length arithmetic and tests within defined fields of full length information words.

Electronic information processing systems may be roughly divided, according to one set of criteria, into two basic groups; viz, non-real time and real time. The distinction is found mainly in the character of reaction required in response to detected contemporaneous events which occur either inside or outside an information processing system. A non-real time information processing system need not necessarily respond to the occurrence of an event within its influence time. Often, however, a real time information processing system must so respond to avoid undesirable or even catastrophic consequences which could otherwise follow the event.

An example of a real time information processing system is a process computer. Process computers are used to monitor and/or control industrial processes or the like. They are real time information processors because they are required to detect events and alter their information flow accordingly to provide output signals which may institute remedial action, sound alarms, or provide some other appropriate response within the influence time of the event. For example, a process computer may be utilized for controlling a steam turbine electric power generating unit for an electric utility. In such a control, unusual conditions on the output line may automatically cause the normal generator protection apparatus to remove the generator from the line. As a consequence, the prime moving turbine tends to speed up very quickly because it is no longer heavily loaded by, and frequency-slaved to, the power grid but is nonetheless still supplied with a vast amount of steam. To keep the turbine and generator from overspeeding, which could cause catastrophic damage, safety valves in the steam supply lines automatically open under these conditions. The process computer must detect these and a myriad of related events and respond quickly to restore the system to a safe condition by analyzing the events and their sequence and issuing appropriate output signals which may cause valves to be opened or closed, breakers to be actuated, alarms to be sounded, etc., to effect a complete shutdown or to prepare the unit for a restart.

In general, a typical process for which process computer control and/or monitoring is contemplated is characterized by the occurrence of many such events or sub-processes, some occurring continuously, some occurring periodically, and others occurring randomly. Hence, a real time information processor is required to perform many functions, seemingly simultaneously. However, a digital computer is by nature a serial device when considered at the instruction level; that is, it can perform its program steps only in a serial fashion, one by one. It is by virtue of the extreme speed at which it operates that a digital computer can be successfully employed in process control and/or monitoring applications. In order that a process computer program may be able to serve the functional needs of the controlled or monitored process, a priority system must be established for the many system functions. Simultaneous occurrence of certain combinations of events may then require a temporary reassignment of priorities. As a consequence of these re-

2

quirements, real time programs are distinctively different from their non-real time counterparts.

A real time computer program becomes in reality a system of programs which service the process functions in accordance with an established priority scheme. These programs operate under an "executive control" program in such a manner that they interrupt one another as the changing process requirements dictate. There must, of course, be an underlying order in the seeming chaos which results from the interaction of so many programs. Thus, it is an inherent requirement of the executive control program that it perform efficiently a large amount of "bookkeeping" or "housekeeping" functions. Indeed, the housekeeping functions, necessary to some degree in all computer programs, prove to be of primary importance in a real time system program.

It becomes apparent that in the creation of real time information processing apparatus, cognizance must be given to the unique requirements of real time programs which distinguish them from programs written for non-real time information processing applications. At the same time, an advancement in the art which improves real time performance may find important utility in a non-real time environment where the advancement is one of time and/or power efficiency.

It is often desirable, during the progression of the functioning program, that only selected portions of an information word be operated upon arithmetically or otherwise altered or that selected word portions be tested against "standard" word portions to detect deviations from the standard. It is also often desirable to perform the same operation upon each of a plurality of sub-words which make up an information word. If the information word can be treated as a whole and the sub-words or "fields" can be continuously variably defined externally from the information word, as many similar alterations, arithmetical functions, or tests can be performed by the execution of a single command as fields may be packed into an information word with a commensurate saving of overall execution time.

It is therefore one object of this invention to provide apparatus for implementing continuously variable sub-word field functions.

It is a more specific object of this invention to provide apparatus to selectively transfer defined sub-word fields between an information processor memory and an accumulator register within the information processor arithmetic unit.

It is another specific object of this invention to provide apparatus to selectively add or subtract defined sub-word fields of a specified information word stored in the information processor memory to or from corresponding fields of an information word temporarily stored in the system arithmetic unit principal accumulator register.

It is yet another specific object of this invention to provide apparatus to selectively test defined fields on an information word temporarily stored in the system arithmetic unit principal accumulator register against corresponding fields of a specified information word stored in the information processor memory for numerical equality or inferiority and to preserve an indication of the test results for subsequent interrogation.

The foregoing objects are achieved, according to one embodiment of the instant invention, by providing apparatus responsive to signals decoded from "Field" command words, which command words have an operand address portion specifying a memory storage location of a full-length information word containing defined fields which may be operated upon arithmetically with or tested against corresponding fields of an information word contained within a principal accumulator register. The fields

are defined by the configuration of a control word temporarily stored in a secondary accumulator register which is serially shifted in synchronism with the principal accumulator register and with a third register into which the specified stored information word has been placed.

Control is exercised by the decoded signals and by the state of the secondary accumulator's lowest order bit position flip-flop for each serial shift to appropriately combine the information from the lowest order bit positions of the principal accumulator register and the third register in a full adder which is provided with a carry flip-flop.

The specific selective, arithmetical, or testing field function carried out during the execution of a Field command is specified by an operation code portion of the command word from which are decoded the signals necessary to implement the execution of the command. The six functions provided by execution of the Field commands, as controlled by the operation codes, are: (1) load defined fields from the specified stored information word into the corresponding fields of the principal accumulator register, (2) store defined fields of the information word in the principal accumulator register into the corresponding fields of the specified stored information word, (3) add defined fields of the specified stored information word to the corresponding fields of the information word in the principal accumulator, (4) subtract defined fields of the specified stored information word from the corresponding fields of the information word in the principal accumulator register, (5) test defined fields of the information word in the principal accumulator register against the corresponding fields of the specified stored information word to determine whether any one or more of the principal accumulator fields contains a lower count than the corresponding fields of the stored information word, and (6) test defined fields of the information word in the principal accumulator register against the corresponding fields of the specified stored information word to determine whether all the defined fields of the former are equal to the corresponding fields of the latter.

A Test Flip-flop is set during the execution of the test functions if the test conditions are met. If the test conditions are not met, the Test Flip-flop is cleared. The state of the Test Flip-flop may subsequently be tested by executing an appropriate command specifically for that purpose.

The subject matter of this invention is particularly pointed out and distinctly claimed in the concluding portion of the specification. The invention, however, both as to organization and method of operation, may best be understood by reference to the following description taken in connection with the accompanying drawings in which:

Process computer system

A diagram showing the organization of a process computer system and its relationship to a controlled or monitored process is presented in FIGURE 1. An Arithmetic and Control Unit 1 performs calculations and other logical operations and also sequences and distributes information throughout the system. It supplies information to and receives information from a Main Memory module 2, an Automatic Priority Interrupt module 5, a Programming Console 6, a Peripheral Control Input/Output Buffer module 7, and a Process Signal Input/Output Buffer module 9.

The Main Memory module 2 typically and in this case contains a random access core storage characterized by its high speed capability. Appropriate control circuitry is provided to permit interchange of information with the Arithmetic and Control Unit 1, a Drum Memory 3, and such additional Bulk Storage Memory Devices 4 as may be required for a given system.

The Drum Memory 3 is a backup storage device for the Main Memory 2. It holds instruction routines and data which can be transferred into the Main Memory 2 upon demand. The Bulk Storage Memory Devices 4 are typically magnetic disk random access storage units and/or magnetic tape storage units used for massive storage of information to which the Arithmetic and Control Unit 1 need not have high speed access but which can be transferred into Main Memory 2 upon demand as may be required.

The Automatic Priority Interrupt module 5 detects and identifies "ready" signals from Peripheral Devices 8 that require testing at relatively long time intervals. A "ready" signal from a peripheral device indicates that it is physically ready to perform its normal function. For example, if a typewriter is "ready" to type, its power is on, its motor is up to speed, and it will have completed any previous request to type a character, i.e., the physical operations which occur within the typewriter to type a character will have been completed so that another character can be typed if required. The Automatic Priority Interrupt module is also used to detect signals which indicate condition changes in the controlled or monitored process. When an interrupt signal is detected, the Arithmetic and Control Unit 1 is alerted, and a program subroutine is initiated at an appropriate time by a program branch to a memory address supplied by the Automatic Priority Interrupt module to service the requesting interrupt according to its relative importance.

The Process Signal Input/Output Buffer module 9 is a communications link between the Arithmetic and Control Unit 1 and the controlled and/or monitored process input and output devices. It acts as a multiplexer for digital and analog inputs and as a multiplexer and amplifier for output signals. Signal inputs may be from contact closures, pulse generators, or measuring devices. The Arithmetic and Control Unit 1 uses the logic and equations stored in Main Memory 2 to decide whether any control or alarm actions are required. If corrective or alarm action is needed, the Arithmetic and Control Unit 1 provides the necessary information through the Process Signal Input/Output Buffer 9 to the digital and/or analog output circuits to change the process control variables or activate the proper alarm devices or displays. A plurality of Process Signal Input/Output Buffer modules may be provided to communicate with a single Arithmetic and Control Unit where the requirements of a specific system exceed the capacity of a single Process Signal Input/Output Buffer module.

The Analog Input Scanner 10 selects and amplifies process analog sensor signals. It also converts analog information into a digital form compatible with that used within the Arithmetic and Control Unit 1 and the other system modules. The Digital Input Scanner module 11 selects and conditions (filters, amplifies, attenuates) contact or digital process inputs. The Multiple Output Distributor

module 12 selects and times digital, decimal, and analog outputs to the controlled and/or monitored process and to operator displays.

The Peripheral Control Input/Output Buffer module 7 communicates with the Arithmetic and Control Unit 1 and is used as a data buffer, translator, and sequencer for the various Peripheral Devices 8, which may include such Input/Output devices as typewriters, paper tape and card readers and punches, etc. A plurality of Peripheral Control Input/Output Buffer modules may be provided to communicate with a single Arithmetic and Control Unit where the requirements of a specific system exceed the capacity of a single Peripheral Control Input/Output Buffer.

The Programming Console 6 provides manual communications with the Arithmetic and Control Unit 1 in machine language for programming and maintenance. In addition, the Programming Console 6 is provided with light displays which show the instantaneous states of various registers and elements within the Arithmetic and Control Unit 1 as an aid to monitoring the system and program performance and condition.

Information representation

The process computer system of FIGURE 1 stores and processes information represented by the binary code in which each digit must be a "one" or a "zero." For a brief explanation of this now commonly used code, one may refer to Chapter 1 of Digital Computer Design Fundamentals by Yaohan Chu, published in 1962 by the McGraw-Hill Publishing Company, Inc. The fundamental unit of information employed in the particular system described is a word of 24 binary digits. The first binary digit or bit of a word is termed the most significant bit and is designated as bit 23. The last binary digit is termed the least significant bit of the word and is designated as bit 0. The binary digits between bits 23 and 0 are accorded successively decreasing orders of significance.

Three general categories of words are employed in the system; viz: (1) data words, (2) command words, and (3) auxiliary words for addressing and control. For convenience a binary word may be more compactly represented by a series of "octal" digits in which each octal digit defines 3 adjacent binary digits. As illustrated in FIGURE 2, any decimal number between zero and seven may be represented by three binary digits so that there are eight total combinations possible, hence that designation "octal." FIGURE 3 illustrates a 24-bit word and the equivalent octal number which represents the binary word given as an example. As will be explained below, the operation codes of the various types of command words are defined by bits 23-18 of the command words. The operation codes may therefore be denoted by two octal digits. A subscript 8 placed after a number indicates octal notation. A subscript 10 placed after a number indicates decimal notation.

The Main Memory module 2 of FIGURE 1 may utilize storage elements of the coincident-current magnetic core type. A brief explanation of magnetic core storage can be found at pages 106, 107, and 108 of Digital Computer Primer by E. M. McCormick, published in 1959 by the McGraw-Hill Book Company, Inc. For this specification, it need only be observed that words stored in the Main Memory module 2 are individually identified by a binary number which represents the address of a specific core cell or storage location in a three-dimensional magnetic core matrix where a desired information word, command word, or control word is stored. If the appropriate binary identification number or address is supplied to the Main Memory module 2, the Memory circuitry can retrieve or "fetch" the designated 24-bit word from the magnetic core storage location and make it available to the Arithmetic and Control Unit 1. The extraction of a previously stored information word from

a core memory may change the magnetic state of individual cores and so destroy the information stored therein. Normal practice in the art is to provide automatic apparatus which immediately restores the same binary word in the same Memory core cell or storage location from which it has been fetched so that, in effect, extracting information from a Memory storage location does not change the information stored there.

Memory storage location addresses are often specified in octal notation. For example, the Memory storage location address 01110110101110 is more compactly identified at 16656₈. It will be observed that, in this example, the binary number is 14 bits in length. For this reason, the most significant octal digit can never be higher than 3. If the binary number had been 13 bits in length, the most significant octal digit could never have been higher than 1. This follows from the conventional practice of dividing the binary word into octal digits by grouping from the least significant to the more significant bits.

The command or instruction words executed by the Arithmetic and Control Unit 1 are divided into six categories: Operand, GEN 1, GEN 2, GEN 3, Quasi, and Step Floating Point (SFP). The format of each of these command types is shown in FIGURE 4. As noted above, the operation codes for all commands are defined by the six most significant bits (23-18) of the command words. The operation code identifies the specific effect to be brought about by the performance of a command or instruction.

Full Operand commands, a sub-category of Operand Commands, are the most commonly used. These commands, which are processed as if the operand were contained by the entire word, are used to perform arithmetic operations, logical operations, index control operations, and data transfers to and from the Main Memory module 2. Bits 13-0 of these command words, the operand address portion, designate the address of the storage location in the Main Memory 2 containing information which is to be used or affected by executing the command. Bit 14 of the Full Operand command words, if a "one" brings about a modification to the operand address known as Relative Addressing which will be described below.

GEN 1 commands are differentiated from other command types by their unique operation code 05₈. These commands are further sub-divided by the microcoding of bits 14-0 of the command word. GEN 1 commands are used primarily to effect bit manipulation within the principal accumulator register of the Arithmetic and Control Unit 1.

GEN 2 commands are differentiated from other commands by their unique operation code 25₈. These commands are also sub-divided by the microcoding of bits 14-0 of the command word. GEN 2 commands are employed within the system to: (1) select modules and devices in the input/output equipment, (2) transfer data to or from these devices, and (3) provide for program control transfers as determined by various internal and external conditions to which the system is responsive.

GEN 3 commands are differentiated from other commands by their unique operation code 45₈. These commands are also sub-divided by the microcoding of the bits 14-0 of the command word. GEN 3 commands are used to manipulate the contents of the principal and secondary accumulator registers and to affect other elements within the Arithmetic and Control Unit 1. GEN 3 commands are also used within Quasi subroutines for speeding up floating point arithmetic operations.

Quasi commands are identified by the presence of the number 7₈ in bit positions 23 through 21 of the command word. These commands are utilized to initiate Quasi subroutines which perform floating point arithmetic operations or other recurring special functions. The Main Memory 2 address of the first command word in a Quasi

subroutine is defined within the operation code of the appropriate Quasi command.

SFP (Step Floating Point) commands are identified by their unique operation code 01₈. They are used within the Quasi subroutines to implement and speed up floating point arithmetic operations. Bits 14-0 of the command words are microcoded to bring about bit manipulations within the Arithmetic and Control Unit 1 of unique significance to the performance of floating point operations.

Bits 17-15 of all command words, denoted the X, or index, bits, are reserved for indicating whether conventional index modification is to be performed on a command before its execution and, if index modification is specified, which index cell contains the modifying or index quantity which is to be the modifier. If bits 17-15 of a command word are all "zeros," no index modification will occur when the command word is transferred to the Arithmetic and Control Unit 1 for execution. If bits 15-17 are any other possible combination (001-111), index modification of the command word will take place by causing the contents of the designated Memory storage location (00001-00007₈) to be added to bit positions 15-0 of the command word. With the most often used command type, Full Operand, the result is normally a change in the operand address portion of the command word. With other command types, however, the command microcoding, and hence the operation to be performed, can be affected by index modification.

Where the total possible number of words which may be stored in the Main Memory module 2 exceeds the definition capability of that part (bits 13-0) of the Full Operand command words which specifies the operand address, a unique form of addressing is utilized to achieve extended addressing capability without increasing the fundamental word length of the information processing system. Bit 14 of Full Operand command words is reserved for specifying whether or not Relative Addressing is to be used with a command word which has been called into the Arithmetic and Control Unit 1 for execution. If bit 14 is a "one," Relative Addressing is specified, and the operand address portion of the command word will be modified arithmetically according to certain defined rules before it is executed such that the total range of addressable storage locations in the Main Memory module 2 is four times as great as that which could be specified by bits 13-0 without the relative addressing capability. If bit 14 is a "zero," Relative Addressing is not utilized, and the command word operand address is that specified directly by bits 13-0 subject to index modification as noted above.

Quasi command words can also be Relative Addressed although the result is not the same as that achieved with Full Operand command words. When a Quasi command word is executed and program control is transferred to the Memory storage location specified by the Quasi command word operation code portion, the binary number contained within the operand address portion is automatically transferred to a predetermined Memory storage location from which it can be extracted for use within the Quasi subroutine if necessary. When a Quasi command word is "Relative Addressed," the ultimate result is a change in the binary number placed into the predetermined Memory storage location rather than an actual change in an operand address per se.

Arithmetic and control unit

FIGURE 5 is a simplified block diagram of the Arithmetic and Control Unit (henceforth, Arithmetic Unit) 1 and the registers within the Main Memory module 2 with which it is in direct communication. The block diagram indicates the functional relationship between the several registers, a Parallel Adder Unit, and three serial full adders. Transfer of information between

registers and other elements of the Arithmetic Unit 1, as indicated by the interconnecting lines of FIGURE 5, is effected by parallel and/or serial transfer of binary digits from the source register or element to the receiving register or element. In the introductory description that follows, only the basic register characteristics and functions and the more usual information flow paths are discussed as a basis for more detailed and expanded discussion of the invention as the specification progresses.

The Parallel Adder Unit (henceforth PAU) 20 is a 24-bit parallel adder with simultaneous (look-ahead) carry propagation between each group of 4 bits which may be enabled or disabled as required. For a general discussion of parallel adder units with simultaneous carry propagation capability, one may refer to pages 390 and 391 of Digital Computer Design Fundamentals by Yaohan Chu and previously referred to in this specification. All parallel arithmetic operations within the Arithmetic Unit 1 are accomplished within the PAU 20. In addition to its arithmetic function, the PAU 20 serves as a "hub" for most parallel transfers of data between the other Arithmetic Unit 1 registers.

The A Register 21 is a 24-bit accumulator for arithmetic operations and bit manipulations. It is capable of either right or left serial shifting in addition to normal, parallel, information exchange with the PAU 20. Parallel transfer of information may be effected between a portion of the A Register 21 and the J Counter 30 for floating point operations. The A Register 21 is also capable of communicating with the Q Register 22, the "F" Full Adder 27, and the "N" Full Adder 29.

The Q Register 22 is a 24-bit auxiliary accumulator used in conjunction with the A Register 21 for double precision arithmetic operations. In addition, the contents of the Q Register 22 are used to define operative fields of the A Register 21 and/or B Register 25 during the performance of Field commands, another sub-category of Operand instruction words, in which only the specified fields (groups of one or more bits) of an information word are affected. The Q Register is also capable of left or right shifting and of normal parallel transfer of information to or from the PAU 20 and is capable of communicating with the "F" Full Adder 27.

The I (Instruction) Register 23 is a 26-bit register which holds the command word being executed at a given time. Two bits, A and B, are interposed between bits 14 and 13 of a standard 24-bit command word when in the I Register 23 to provide a 16 bit operand field for extended memory addressing. Information transferred to or from the I Register 23 normally moves in parallel although portions of the I Register 23 may be serially shifted under certain conditions. The I Register 23 is capable of communicating with the PAU 20, the P Register 24, the "I" Full Adder 28, the Memory Address Register 32, and the Memory Data Register 33.

The P (Program Location) Register 24 is a 16-bit register which normally specifies the address of the storage location in the Main Memory module 2 from which the next command to be executed is to be extracted. All information is transferred to and from the P Register 24 in parallel. The P Register 24 is capable of communicating with the Parallel Adder Unit 20, the I Register 23, the H Register 26, and the Memory Address Register 32.

The B Register 25 is a 24-bit parallel-entry buffer register disposed between the Main Memory module 2 and the processing registers of the Arithmetic Unit 1. All information passing to or from the storage locations in the Main Memory module 2 is routed through this register via the Memory Data Register 33. The B Register 25 is capable of being right shifted during the performance of certain commands with which the B Register 25 is utilized as a functional information processor as well as a buffer. Information is transferred between the B Register 25 and the PAU 20 in parallel. The B Register 25

is also capable of communicating with the "F" Full Adder 27, the "I" Full Adder 28, and the "N" Full Adder.

The H (Holding) Register 26 is a 16-bit register used primarily to provide temporary information storage during the execution of certain "extended function" commands. This register is capable of accepting parallel data from the PAU 20 and transferring parallel data to the PAU 20, the P Register 24, and the Memory Address Register 32.

The "F" Full Adder 27 is used to implement arithmetic and logical manipulation on fields specified by the Q Register 22 during the performance Field commands and also to update a portion of List Control Words during the execution of List commands which affect certain storage locations is specified portions of the Main Memory 2.

The "I" Full Adder 28 is used to compute, from information contained within List Control Words, the relative location of items to be removed or appended to lists stored in the Main Memory module 2 during the performance of List commands.

The "N" Full Adder 29 is used to implement arithmetic and logic manipulations of the A Register 21 and to update second and third portions of List Control Words during the performance of List commands.

The J Counter 30 is a 5-bit counter used to control information manipulation and certain aspects of timing during the execution of a number of commands which require counting in one form or another, some according to variable conditions.

The Input/Output (henceforth, I/O) Selector Hub 31 provides Arithmetic Unit communications with the Peripheral Control Input/Output Buffer 7, the Process Signal Input/Output Buffer 9, and the Programming Console 6. The I/O Selector Hub enables one of a plurality of selectable 24-bit I/O information channels during the execution of certain commands. All parallel data transfers from Input/Output devices are routed through the I/O Selector Hub 31 to the PAU 20 for further distribution within the Arithmetic Unit 1.

The Memory Address Register 32 is 16-bit register which is an integral part of the Main Memory module 2 rather than the Arithmetic Unit 1. However, it receives a 16-bit truncated word directly from the P, I, or H Registers of the Arithmetic Unit 1, which word specifies the Memory storage address for the next stored 24-bit word which is to be transferred from Main Memory 2 into the Arithmetic Unit 1 via the Memory Data Register 33.

The Memory Data Register 33 is also an integral part of the Main Memory module 2. It is a 24-bit register which holds any word just extracted from a Memory storage location in response to a specific address having been placed in the Memory Address Register 32 and a Memory request having been made by the Arithmetic Unit 1. The Memory Data Register 33 communicates with the B Register 25 and I Register 23 of the Arithmetic Unit.

Logic and logic combinations

In a fundamentally binary information processing system, any given signal representing a single bit of information must always be either true or false or, as it is more commonly expressed, either "one" or "zero." Ordinarily, these states are represented within an information processor, other than as stored in Memory devices, by two discrete voltage levels. For example, a voltage level of nominally five volts positive may correspond to a binary "one" signal, and a voltage level of nominally zero volts to a binary "zero." The choice of voltage levels is arbitrary except for the consideration of using specific types of logic circuitry which may be preferred or prescribed. It is not uncommon for the two discrete voltage levels which represent "one" and "zero" conditions to be different in different logic areas of an information processing system; that is to say, a system in which "ones" and

"zeroes" are normally represented by five volts positive and zero volts levels respectively may include areas in which conditions require a wider voltage disparity and, perhaps, a polarity inversion. These areas might have logic voltage levels, for example, of 18 volts negative for "ones" and six volts positive for "zeros." For these reasons, it is standard practice to explain binary logic systems in straightforward terms of "one" and "zero" conditions without excessive concern for the precise arbitrary voltages representing these conditions.

Temporary storage of a bit of information may be effected by deliberately setting a bistable device to one or the other of its stable states to represent a "one" or a "zero." The bistable device most widely used in electronic information processors is the well known "flip-flop." A flip-flop is said to be in either the "one" state or the "zero" state and has the capability of retaining a state into which it has been placed until it is operated upon and forced into its alternate state. A change of state of a flip-flop is normally brought about by applying a voltage pulse to a "set" or "clear" (sometimes called "reset") input. As a practical matter, a flip-flop is usually designed to respond to voltage transients so that a change of state occurs, according to design, on the trailing or leading edge of a voltage pulse applied to a flip-flop input.

The state of a flip-flop may be reflected in one or more outputs, and a flip-flop is usually provided with both "one" and "zero" outputs. Should a flip-flop be in the "one" or set state, the "one" output would be true and the "zero" output would be false. If positive five volts and zero volts represent "one" and "zero" signal levels within the local logic areas of the system, the "one" output would be positive five volts and the "zero" output would be zero volts. On the other hand, if the flip-flop is in the "zero" or cleared state rather than set, the "one" output would be zero volts or false and the "zero" output would be positive five volts or true.

FIGURE 6A shows a logic symbol for a flip-flop with its input and output terminals indicated. FIGURE 6B is a voltage/time diagram which illustrates the response characteristics of a flip-flop to set and clear pulses applied to the appropriate input terminals.

Information requiring a plurality of bits for definition may be temporarily stored in a group of flip-flops which make up a register. Hence, a 24-bit word may be placed in a 24-bit register, and the state of each flip-flop in the register may be ascertained by observing the voltage levels at the individual "one" and "zero" outputs. The flip-flops of a register may be interconnected to permit serial shifting of the information bits in unison to the next higher order or next lower order bit position relative to each. A brief explanation of serial shifting may be found on pages 95 and 96 of Digital Computer Primer by E. M. McCormick and previously referred to in this specification. Entry of information into a register may be performed serially or in parallel to each individual flip-flop in unison. The flip-flops of a register may also be interconnected such that the register functions as a counter to accumulate intermittent pulses from one or more pulses.

Movement of information between the registers of an information processor and many other related functions are performed in relative synchronism. A common time base generator is therefore required; and this conveniently may be a stable oscillator and a suitable wave shaping circuit to produce a train of regular, rectangular pulses often designated the "Clock." The "one" and "zero" positions of a Clock pulse train may be time symmetrical or asymmetrical as may be appropriate for the system which it governs. FIGURE 7A is a block representation of a Clock Generator 35, and FIGURE 7B is a diagram showing the time and voltage dimensions of a 2.94 megacycle Clock signal suitable for use in an information processing system with which the present invention may be practiced.

Generally, two or more output signals from flip-flops and/or other bistable devices such as switches are com-

bined logically, sometimes with and sometimes without a Clock or other timing signals, by "gates" to provide input signals to other flip-flops and to provide gating signals which are logically combined with binary information signals to control information movement within the system, both as to path and as to relative time.

A gate has a single output which reflects logically the instantaneous state of its inputs. These inputs may, for logical design purposes, be any number required. Gates with certain distinctive characteristics are conventionally designated AND gates, OR gates, NAND gates, NOR gates, and NOT gates. Gates are represented in logic diagrams by standard symbols according to their characteristics, which characteristics may be summarized in a truth table for each type of gate. For example, a logic notation symbol for a two-input AND gate and its truth table are shown in FIGURES 8A and 8B, respectively. It will be observed that only when inputs A and B are both "ones" will the output W be a "one." If one or more of the inputs should change to "zero," the output would switch to "zero."

FIGURE 9A shows a logic notation symbol for a two-input OR gate and FIGURE 9B its truth table. It will be observed that if one or the other or both the inputs F and G is "one" then the gate output will be "one." If the inputs are all "zeros," the output X will be "zero."

Equivalent logic notation symbols and their corresponding truth tables for NAND and NOR gates are shown in FIGURES 10A, 10B and 11A, 11B respectively.

Another element widely used in binary logic networks is the logical inverter which has a single input and a single output and, as its name implies, converts a "one" input to a "zero" output and a "zero" input to a "one" output. A logic notation symbol and truth table for the logical inverter are shown in FIGURES 12A and 12B. The logical inverter is also known as the NOT gate.

A three-input, four-output logic element known in the art as a "full adder" is represented by the logic notation symbol shown in FIGURE 13A. The characteristics of a full adder are summarized in a table presented in FIGURE 13B. The S and $\bar{S}$ outputs are complementary "sum" signals, and the C and $\bar{C}$ outputs are complementary "carry" signals. Full adders are used, often in conjunction with "carry" flip-flops, to perform binary arithmetic. It may be observed that the full adder characterized in FIGURE 13B "adds" in response to "zero" inputs rather than "one" inputs. This is merely a matter of circuit preference, and full adders responding to "one" inputs are also well known in the art.

In order to achieve meaningful and orderly movements of information between the various registers and other elements of an information processor, after a need for specific movements and combinations of movements has been established, gating signals must be generated or issued which permit the prescribed movements of information at the desired time and inhibit any undesirable movements of information at the same time. The exact manner in which a specific signal may be generated according to precisely defined conditions within a computer system at certain precisely defined times has become a matter of common knowledge within the art. Generally speaking, a signal issues, usually as a gate output, when all requisite conditions are satisfied in its logic chain. The conditions in a chain are themselves represented by other signals which may be individually dependent upon a higher order logic chain relative to the specific signal of interest. Alternatively, it is manifest that these higher order logic chains can simply be considered elements of the total set of conditions upon which the issuance of the ultimate signal depends. The origin of a given signal can thus be traced back to a unique set of conditions each of which depends upon the state of a bistable device at a given instant of time and which may or may not be logically combined with timing signals such as a Clock.

A unique mnemonic designation is conventionally assigned to each unique signal within a binary information processing system. In the present system, signals are identified by four character mnemonic designations. The Clock, for example, is designated TCKA. Following standard logic notation practice, a signal designated TCKA is the logical inversion of TCKA as indicated by the bar over the mnemonic. Whenever TCKA is "one," TCKA must be "zero"; and whenever TCKA is "zero," TCKA must be "one."

The set of conditions which must be fulfilled for a given signal to be "one" may be expressed by the classical logic or Boolean equation. The use of Boolean Algebra to represent binary logic combinations has become so universally known and practiced in the art that it need not be discussed at length here. An elementary treatment, adequate for an understanding of this specification, may be found in Appendix A of Digital Computer Primer by E. M. McCormick, previously referred to in this specification. For a more extended discussion of Boolean Algebra and its use in logical design, one may see chapters 3 and 4 of Digital Computer Design Fundamentals, by Yaohan Chu and previously referred to in this specification.

It is of some importance to understand that what is commonly and conventionally designated a "signal" in a binary information processor is often conceptually both a signal and an electrical point where the signal is represented as a function of time by one of two discrete voltage levels. For this reason, a logic equation wherein a given signal is expressed in terms of other signals also defines the orientation and interconnection of logic elements, such as gates and inverters, by which the signal is generated. As an example, assume that a combination of logic elements is to produce a "one" output signal when either one, but not both, of two input signals A and B is "one." Further, assume a restriction to the use of AND gates, OR gates, and NOT gates to achieve the desired result.

A logic element combination that meets these requirements and restrictions is presented in FIGURE 14. If a "one" signal is present at either A or B, but not both, a "one" output will be realized at X, the output from AND gate 42. The AND gate 40 is not enabled since one or the other of its two enabling requirements has not been met, and, as a consequence, its output C is "zero." The NOT gate 41 converts this "zero" signal to a "one" signal at point D to enable one input of the AND gate 42. The OR gate 43 is enabled since it will respond to a "one" signal at either A or B to produce a "one" signal at E which enables the remaining input of the AND gate 42. If "one" signals are present at both A and B, a "zero" signal will appear at point X. The AND gate 40 will produce a "one" output at C since both its input signals are "one;" the NOT gate 41 will therefore produce a "zero" output at point D to disable one input of the AND gate 42. If "zero" signals are present at both A and B, a "zero" output will appear at point X. The OR gate 43 will be disabled since neither of its inputs is "one." The OR gate 43 will therefore produce a "zero" output at point E to disable one input of the AND gate 42.

The logic combination shown in FIGURE 14 is sometimes referred to as an EXCLUSIVE OR gate because of its one-or-the-other-but-not-both characteristic. The logical relationship of the signals employed in FIGURE 14 are defined by the equation $C = \bar{A}\bar{B} + \bar{A}B$ which is read, according to conventional Boolean notation discussed in the above-cited references, as: C must be "one" when A but not B is "one" or when B but not A is "one."

If NAND gates are used, the logic element combination of FIGURE 15 will function in the same logical manner as that shown in FIGURE 14. The NAND gate 44 of the FIGURE 15 combination performs the functions of both

the AND gate 40 and the NOT gate 41 of the FIGURE 14 combination.

The means by which a skilled logical designer, who is aware of which logic elements are available and of their characteristics, can determine the exact logic elements and exact interconnection required for a logic chain ending in a signal which has been defined by a logic equation is explained at length in many standard texts. One may refer to Chapter 3 and, particularly Chapter 4 of Digital Computer Design Fundamentals by Yaohan Chu and previously referred to in this specification. It is readily apparent from the above that the creation of a unique control signal defined in terms of other control and timing signals is well known in the art and no further explanation will be given here. In describing the invention, the more important control signals are defined in terms of their characteristics, and their origin is shown in blocks designated Instruction Decoding, Gating Signal Generation, and Timing.

Timing and normal sequence control states 1 and 2

To maintain an orderly and efficient succession of operations within the Arithmetic Unit 1, Sequence Control logic 50 provides five mutually exclusive Sequence Control States which are defined by five Sequence Control Flip-flops designated F1SC01, F1SC02, F1SC03, F1SC04, and F1SC05 as shown in the Timing Block Diagram of FIGURE 16.

The Sequence Control State 1 Flip-flop F1SC01 defines the "fetch" cycle for all commands. The fetch cycle is that period during which a command stored in Main Memory 2 is requested, is transferred from Main Memory 2 to the Arithmetic Unit 1, and is routed into the I Register 23. In addition, the count in the P Register 24 is usually incremented during Sequence Control State 1, and other information movement among the registers may occur. A few commands which can be completed by a simple group of operations are completely executed during Sequence Control State 1. Relative Addressing, when specified by bit 14 of the command word, also occurs during Sequence Control State 1. Timing signal SC1A is "one" when the Sequence Control State 1 Flip-flop F1SC01 is set.

The Sequence Control State 2 Flip-flop F1SC02 defines the sequencing cycle when index modification occurs. In addition, Sequence Control State 2 is entered during the performance of several commands that utilize the X bits (17-15) of a command word for purposes other than normal index modification. Sequence Control State 2, when required, is normally entered immediately following Sequence Control State 1. Timing Signal SC2A is "one" when the Sequence Control State 2 Flip-flop F1SC02 is set.

The Sequence Control State 3 Flip-flop F1SC03 is used to provide additional bit manipulation time for a number of commands under certain conditions prior to further execution. The time extent of Sequence Control State 3 is determined by the requirements of the individual commands. Timing signal SC3A is "one" when the Sequence Control State 3 Flip-flop F1SC03 is set.

The Sequence Control State 4 Flip-flop F1SC04 defines the final execution state for most commands. Sequence Control State 4 is entered following Sequence Control States 1, 2, or 3 depending on the nature of the command being executed. Like Sequence Control State 3, Sequence Control State 4 may be time-extended as required for individual commands. Timing signal SC4A is "one" when the Sequence Control State 4 Flip-flop F1SC04 is set.

The Sequence Control State 5 Flip-flop F1SC05 defines a time period necessary for performing additional functions required to complete the execution of a few commands. Timing signal SC5A is "one" when the Sequence Control State 5 Flip-flop F1SC05 is set.

The timing control signals required for optimum operation within each Sequence Control State and for insuring

timely changes from one Sequence Control State to another are generated by a Delay Time Counter 51 and a Sequence Time Counter 52 in conjunction with the Clock signal TCKA provided by the Clock Generator 35. In FIGURE 20 and subsequent timing diagrams, the Clock signal TCKA is drawn symmetrically for convenience rather than asymmetrically as in FIGURE 7B. The Sequence Time Counter 52 comprises three flip-flops: F1TCSA, F1TCSB, and F1TCSC. The timing signals decoded from the Sequence Timing Counter 52 are tabulated in FIGURE 17 along with the logic equations for the counter advancing pulses which are developed in the logic immediately associated with the Sequence Time Counter 52.

The Delay Time Counter 51 comprises five flip-flops: F1TAFF, F1TBFF, F1TCFF, F1TDFF, and F1TEFF. It is used to provide special control signals during the execution of commands requiring extension of the normal durations of Sequence Control States 3 and/or 4. The Delay Time Counter 51 is preset during Sequence Control States 3 and/or 4 of these commands to a count less than 30_8 and is then incremented by the Clock Signal TCKA. During all other Sequence Control States, the Delay Time Counter 51 is preset to 30_8 and is inhibited from being incremented. A Delay Time Counter Complete signal TPI3 becomes "one" when the Delay Time Counter 51 count reaches 30_8 and the Sequence Time Counter 52 is in the TT4E state. When this condition is attained, a Last Pulse signal TLPS is generated coincident with TCKA. The trailing edge of signal TLPS during any Sequence Control State clears the Sequence Time Counter 52, and the timing cycle for the next Sequence Control State is entered. At the trailing edge of signal TLPS of the final Sequence Control State for the execution of any command, Sequence Control State 1 is re-entered to initiate execution of the succeeding command.

The primary function of Sequence Control State 1 is to bring a command stored in Memory at an address specified by the contents of P Register 24 into the Arithmetic Unit 1 so that it may be decoded and executed. In addition, the P Register 24 is normally incremented during Sequence Control State 1 so that it will contain the address of the next command to be executed if the normal program sequence is followed. It may be noted here that certain conditions or commands can dictate a deviation from the straight instruction sequence provided by the P Register 24.

The primary purpose of Sequence Control State 2 is to implement conventional index modification when bits 15, 16, and 17 of a command word being executed are not all "zeros." This condition will have been detected during TCTA time of Sequence Control State 1 and appropriate signals generated so that Sequence Control State 2 is entered at the end of Sequence Control State 1.

The signals generated and the information flow scheme which takes place during Sequence Control States 1 and 2 is identical or nearly so for all commands. FIGURES 18 and 19 are block diagrams which indicate the information flow paths established during normal Sequence Control States 1 and 2, respectively; and FIGURE 20 is a timing diagram of the important gating signals which permit the proper paths to be established. In addition, the normal timing signals utilized within every Sequence Control State are included in the timing diagram of FIGURE 20.

The operation and function of normal Sequence Control States 1 and 2 may best be understood by considering the following description in conjunction with FIGURES 1, 5, 18, 19, 20, and 21. FIGURE 21 is a block diagram showing the logic areas of the Arithmetic Unit 1 from which the more important signals issue.

It should be noted that the Main Memory module 2 operates asynchronously with the Arithmetic Unit 1. To fetch a stored command word, Sequence Control State 1

is entered, and the Main Memory module 2 is alerted that a request is being made by the MREQ signal as shown in the timing diagram FIGURE 20. Simultaneously, the contents of the P Register 24 are gated to the Memory Address Register (MAR) 32 by the MAMP signal. The contents of the specified storage location in the Main Memory module 2 are fetched and placed into the Memory Data Register (MDR) 33 by the Main Memory module 2 logic functioning independently from the Arithmetic Unit 1. When the requested word is available from the Memory Data Register 33, the Main Memory module 2 generates a Data Ready signal CDRA to the Arithmetic Unit 1; and, during TCT2 time, the contents of the Memory Data Register 33 are gated to the B Register 25 by the BDOB signal. Additionally, Memory Data Register 33 bits 23-14 are gated to the I Register 23 bit positions 23-14 by the IDOC signal so that operation code decoding may commence. During TCTA time, B Register bits 13-0 are gated to bit positions 13-0 of the PAU 20 by the UBLA signal. At the trailing edge of signal TLPS during Sequence Control State 1, bits 15-0 of the PAU 20 are gated to bit positions A, B, 13-0 of the I Register 23 by the IAUI signal and to the H Register 26 by the HAUH signal.

Normal incrementation of the P Register 24 also occurs during Sequence Control State 1 and is brought about in the following manner without disturbing the information flow between the various Arithmetic Unit 1 elements. During TCTS time, the contents of the P Register 24 and a count of one are simultaneously gated to the PAU 20 by the UPAU and UENC signals, respectively. The output signals from the PAU 20 at this time represents the desired sum, $P+1$. This sum is gated to the H Register 26 by the HAUH signal which occurs during TCT2 time. At the trailing edge of signal TLPS, the contents of the H Register 26 are gated to the P Register 24 by the signal PXHP as the output signals from the PAU 20 bit positions 15-0 are gated to the H Register by the HAUH signal.

Thus, at the end of a normal Sequence Control State 1, the I Register 23 contains the command which has been requested from Main Memory module 2, the P Register 24 count has been incremented by one, the operand address portion of the fetched command word is in the H Register 26 and the next required Sequence Control State may be entered to continue the execution of the command. It will be observed that the operation code portion of the command word is in the I Register 23 during TCTA time of Sequence Control State 1, and appropriate control signal generated from instruction decoding become available at that time to influence: (a) the remainder of Sequence Control State 1 (as required for a very few commands), (b) the Sequence Control State which will be entered next following signal TLPS, and (c) the action to be taken during the succeeding Sequence Control States.

Assuming that bits 17-15 of the command word of the instruction being executed are not all "zeros," Sequence Control State 2 will be entered following Sequence Control State 1. The signal MREQ again becomes "one" to indicate a request to the Main Memory module 2. Simultaneously, the contents of the I Register 23 bit positions 17-15 are gated to the Memory Address Register 32 bit positions 2-0 by the MAMX signal to specify the memory storage location indexing quantity to be fetched. This is conveniently one of the low order memory storage locations 00001 to 00007_8 ; therefore, the higher order bit positions of the Memory Address Register 32 are simply cleared by the MAMX signal. When the CDRA signal indicates that the requested modifying data is available from the Memory Data Register 33, its contents are gated to the B Register 25 by the BDOB signal during TCT2 time. During TCTA time, the contents of the B Register 25 are gated to the PAU 20 by the UBLA and UBUA signals. Simultaneously, the contents of the I Register 23

bit positions A, B, 13-0 are also gated to the PAU 20 by the UIAU signal. The output signals from the PAU 20 then represent the sum of the operand address portion of the command word present in the I Register 23 and the modifying word or index quantity stored in the specified index core cell. At the trailing edge of signal TLPS, the sum is gated from the PAU 20 bit positions 15-0 to the I Register 23 bit positions A, B, 13-0 by the IAUI signal, and the sequence control timing enters the next appropriate Sequence Control State according to the requirements of the individual command temporarily stored in the I Register 23. A few commands which affect or test the index cells use the index bits for instruction control and do not change the operand address portion of the command word.

In the following detailed description of the present invention, the assumption is made that the exemplary commands are not indexed in order that the timing charts do not become unnecessarily complex. It is to be understood, of course, that these commands can be index-modified in the manner just described.

Six fully independent Full Operand command words are provided in the present system to achieve a complete range of variable field arithmetic functions. The configuration of the fields is always defined by the contents of the Q Register 22 which will have previously been loaded with the appropriate definition word in any convenient manner.

A LOAD FIELD command is arbitrarily assigned the mnemonic designation LDF and the operation code 23₈. In response to the LDF command, selected bits from an information word stored in a Memory storage location (assume an address Z) specified by the operand address portion of the LDF command word, are placed in the corresponding bit position of the A Register 21. For each bit position of the Q Register 22 that is a "one," the corresponding bit position of the information word stored in Memory storage location Z is placed in the corresponding bit position of the A Register 21. For each bit position of the Q Register 22 that is a "zero," the corresponding bit position in the A Register 21 remains unchanged.

The following example illustrates the effect of the execution of an LDF command on the A Register 21. Five bit registers are illustrated for simplicity.

Contents of Z ----- 00111
Prior Contents of A ----- 10100
Contents of Q ----- 01110
New Contents of A ----- 10110

A STORE FIELD command is arbitrarily assigned the mnemonic designation STF and the operation code 13₈. In response to the STF command, selected bits from an information word temporarily stored in the A Register 21 are placed in the corresponding bit position of a Memory storage location Z specified by the operand address portion of the STF command word. For each bit of the Q Register 22 that is a "one," the corresponding bit of the information word temporarily stored in the A Register 21 is placed in the corresponding bit position of Memory storage location Z. For each bit position of the Q Register 22 that is a "zero," the corresponding bit position of Memory storage location Z remains unchanged.

The following example illustrates the effect of the execution of an STF command on Memory storage location Z. Five bit registers are illustrated for simplicity.

Prior Contents of Z ----- 00111
Contents of A ----- 10100
Contents of Q ----- 01110
New Contents of Z ----- 00101

An ADD FIELD TO A command is arbitrarily assigned the mnemonic designation AFA and the operation code 03₈. In response to the AFA command, selected bits of an information word stored in a Memory storage location specified by the operand address portion of the

AFA command word are added to the corresponding bits of the contents of the A Register 21. For each bit position of the Q Register 22 that is a "one," the corresponding bits of the information word in Memory storage location Z and the corresponding bits of the contents of the A Register 21 are summed and the result is placed in the A Register 21. Carries resulting from the summation are propagated to the next sequential bit position only if the corresponding next sequential bit position of the Q Register 22 is a "one." For each bit position of the Q Register 22 that is a "zero," the corresponding bit of the A Register 21 remains unchanged.

The following example illustrates the effect of the execution of an AFA command on the A Register 21. Five bit registers are illustrated for simplicity.

Contents of Z ----- 00111
Prior Contents of A ----- 10100
Contents of Q ----- 01110
New Contents of A ----- 11010

A SUBTRACT FIELD FROM A command is arbitrarily assigned the mnemonic designation SFA and the operation code 22₈. In response to the SFA command, selected fields of an information word stored in Memory storage location Z specified by the operand address portion of the SFA command word are subtracted from the corresponding fields of the A Register 21. For each bit position of the Q Register 22 that is a "one," the corresponding bit of the information word stored in Memory storage location Z is subtracted from the corresponding bit of the A Register 21 and the result is placed in the A Register 21. Carries resulting from the subtraction are propagated to the next sequential bit position only if the corresponding next sequential bit position of the Q Register 22 is a "one." For each bit position of the Q Register 22 that is a "zero," the corresponding bit of the A Register 21 is unchanged.

The following example illustrates the effect of the execution of the SFA command on the A Register 21. Five bit registers are illustrated for simplicity.

Contents of Z ----- 00111
Two's Complement of Z in Specified Bits ----- 01010
Prior Contents of A ----- 10100
Contents of Q ----- 01110
New Contents of A ----- 11110

It will be observed that the subtraction in the specified bits has been effected by adding the two's complement of the binary number stored in the specified bits of Memory storage location Z to the specified bits of the original contents of the A Register 21. This method of binary subtraction and its use with the present invention will be discussed in detail below.

A TEST FIELD LESS command is arbitrarily assigned the mnemonic designation TFL and the operation code 12₈. In response to the TFL command, selected fields in the A Register 21, as defined by "ones" in the Q Register 22, are compared to corresponding fields of an information word stored in Memory storage location Z specified by the operand address portion of the TFL command word. If any defined field in the A Register 21 is not less than the corresponding field in the information word stored in Memory storage location Z, A Test Flip-flop is cleared and may subsequently be tested for that state by executing an appropriate instruction specifically for that purpose.

A TEST FIELD EQUAL command is arbitrarily assigned the mnemonic designation TFE and the operation code 02₈. In response to the TFE command, selected fields in the A Register 21, as defined by "ones" in the Q Register 22, are compared to corresponding fields of an information word stored in Memory storage location Z specified by the operand address portion of the TFE command word. If all defined fields in the A Register 21 are equal to the corresponding fields in the information word stored in Memory storage location Z, the Test Flip-

flop remains set and may subsequently be tested for that state by executing an appropriate instruction specifically for that purpose.

When any one of the six field commands is called into the Arithmetic Unit 1 for execution, a normal Sequence Control State 1 is passed through. Therefore, at the end of Sequence Control State 1 for a Field command, the I Register 23 will contain the fetched Field command word, the H Register will contain the operand address portion of the command word, and the P Register 24 will have been incremented in the normal manner.

It will be remembered from the detailed description given above of a normal Sequence Control State 1 that the command word operation code portion is gated to the I Register 23 by the trailing edge of the IDOC signal where it is then available for instruction decoding. Whenever any one of the Field command words is decoded, the DFLD signal becomes "one" and controls a number of operations that are common to all the Field commands.

Referring to the timing diagrams FIGURES 22-27 and to the logic diagram FIGURE 28, it will be observed that the Delay Time Counter 51 is cleared as a matter of course near the beginning of each Sequence Control State by the trailing edge of the TTOB signal which is derived by combining the TCKA and TTOE signals in the AND gate G500 and passing the output signal from G500 through a 200 nanosecond delay element.

The AND gate G501 of FIGURE 28 will be enabled only when the Delay Time Counter 51 has been incremented to a count of 30_8 because its input signals are from the "one" outputs of the F1TAFF and F1TBFF Flip-flops and the "zero" outputs from the F1TCFF, F1TDFF, and F1TEFF Flip-flops. Until this condition is reached, the output signal from G501 is a "zero." The output signal from G501 is inverted through the NOT gate I502 which therefore impresses an enabling signal onto one input of another AND gate G503 having the timing signals TCKA and TT4E as its other inputs. The output signal from G503, TDCL, is utilized to increment the Delay Time Counter 51. Since G501 becomes enabled when the Delay Time Counter 51 count reaches 30_8 , the polarity inversion through I502 will disable G503 when that count is reached to inhibit further incrementation of the Delay Time Counter 51.

The output signal from the AND gate G501 is also inverted through another NOT gate I504 which drives one input of AND gate G505 having the timing signals TCKA, SC4A, and TT4E and the decoded signal DFLD as its remaining inputs. Thus, the output signal from G505, FSRF, will be a string of 30_8 (24_{10}) pulses occurring in coincidence with TCKA during TT4E time of Sequence Control State 4 of the Field commands.

It will be observed in the logic diagram in FIGURE 29 that the FSRF signal is applied as one input to AND gates G510 and G511 associated with the B Register, AND gates G512 and G513 associated with the A Register 21, and AND gates G514 and G515 associated with the Q Register 22. In FIGURE 29, the FSRF signal is also symbolically applied to the remaining stages of these registers to indicate that interstage AND gates, not shown, are enabled to permit normal serial right shifting so long as the FSRF pulse train is present.

LDF

Consider now the execution of an LDF command with reference to its timing diagram FIGURE 22 and to the logic diagram FIGURE 29. When the LDF command word operation code portion is in the I Register 23, the DLDF signal, as well as the DFLD signal, becomes "one." Following a normal Sequence Control State 1 and assuming that the LDF command is not index modified, Sequence Control State 4 is entered. During the whole of Sequence Control State 4, Memory is addressed from the I Register 23 because the MAMI signal is "one." When the word stored in the specified Memory storage location is available from the Memory Data Register 33, it is gated to the B Register 25 by the BDOB signal.

The DLDF signal is one input to an OR gate G519 so that when the LDF command is decoded, G519 is enabled, and its output signal is applied as one input to another AND gate G520. The other input to G520 is driven from the "one" output of the Q Register 22 bit position 00 flip-flop; thus whenever the Q Register 22 is right shifted during Sequence Control State 4 of the execution of an LDF command, G520 will be enabled or disabled according to whether the information temporarily held in the Q00 Flip-flop is a "one" or a "zero." The output signal from G520 is one input to an OR gate G522 so that the output signal from G522 reflects directly the state of the Q00 Flip-flop during the execution of the LDF command. The output signal from G522 is applied to one input of a NAND gate G517 which drives the B input to the "F" Full Adder 27.

The DLDF signal is also one input to another OR gate G539. When the DLDF signal is "one," the "one" output signal from G539 enables one input to an AND gate G540. The other input to G540 is from the "one" output of the B Register 25 bit position 00 flip-flop so that the output signal from G540 reflects directly the information in the B00 Flip-flop for each shift during the execution of the LDF command. The output signal from G540 is one input to an OR gate G541, and the output signal from G541, which will simply follow the output from G540 for the LDF command, drives the remaining input to the NAND gate G517. Thus, when the NAND gate G517 is fully enabled (Q00 and B00 contain "ones" for the LDF command) and its output becomes "zero," the B input to the "F" Full Adder 27 is enabled.

The output signal from G519 also enables one input of another AND gate G528 when the DLDF signal is "one." The other input to AND gate G528 is driven from the "zero" output from the Q Register 22 bit position 00 flip-flop. The output signal from G528 is one input to an OR gate G530; therefore, during the execution of the LDF command, the output signal from the OR gate G530 will be the inverse of the Q00 Flip-flop state during the execution of the LDF command.

It is apparent from the above description that the state of the Q Register bit position 00 flip-flop causes a toggling action partially enabling either the NAND gate G516 or the NAND gate G517 so that either the A Register 21 bit position 00 flip-flop or the B Register 25 bit position 00 flip-flop "one" output is effectively inverted and impressed on the A or B input to the "F" Full Adder 27.

It will be observed that the "F" Carry Flip-flop 27A is always cleared by the trailing edge of the SC1A signal applied to the clear input through the OR gate G526. Since, for each FSRF pulse, only the A or the B input to the "F" Full Adder 27, but not both, will be enabled if the appropriate register contains a "one" in its lowest order bit, no carry can result during the execution of an LDF command. Therefore, the "F" Carry Flip-flop 27A remains cleared during Sequence Control State 4, and the S and $\bar{S}$ outputs from the "F" Full Adder 27 reflect the state of the lowest order bit position flip-flop for the appropriate register as dictated by the state of the Q00 Flip-flop for each FSRF pulse.

The DLDF signal is one input to an OR gate G531, and the output signal from G531 enables one input each of a pair of AND gates G533 and G532 during execution of the LDF command. The other inputs to AND gates G533 and G532 are driven by the "F" Full Adder 27 S and $\bar{S}$ outputs respectively. Thus, either G533 or G532 will be enabled according to whether the selected register's lowest order bit is a "one" or a "zero." The output signals from the AND gates G532 and G533 drive one input of OR gates G534 and G535, respectively, so that the output signals from G534 and G535 also reflect the state of the selected register's lowest order bit. The output signals from G534 and G535 drive one input of AND gates G513 and G512, respectively. As previously described, the remaining input to the AND gates G512 and G513, which drive the set and clear inputs to the A Register 21 bit position

23 flip-flop, are enabled by the FSRF signal so that the desired information is right shifted into the A Register 21 where it will be properly positioned after the last FSRF pulse.

When the Q Register 22 is right shifted during the execution of the LDF command and all the other Field commands, it is also circular shifted so that, after the final FSRF pulse, the Q Register 22 information will be unchanged. This is achieved by applying the "one" and "zero" outputs from the Q00 Flip-flop to one input of G514 and G515, respectively. As previously described, the remaining input to the AND gates G514 and G515, which drive the set and clear inputs to the Q Register 22 bit position 23 flip-flop, are enabled by the FSRF signal so that the original information is right shifted back into the Q Register 22 where it will be properly positioned after the last FSRF pulse.

When the B Register 25 is right shifted during the execution of the LDF command and all the other Field commands, the signals from the S and $\bar{S}$ outputs of the "F" Full Adder 27 are impressed on one input respectively of AND gates G510 and G511. As previously described, the remaining input to the AND gates G510 and G511, which drive the set and clear inputs to the B Register 25 bit position 23 flip-flop, are enabled by the FSRF signal so that the information word shifted from the "F" Full Adder 27 is always right shifted into the B Register 25 where it will be properly positioned after the last FSRF pulse.

At the trailing edge of the TLPS signal of Sequence Control State 4 of the execution of the LDF command, Sequence Control State 1 is reentered to fetch the next command word to be executed from the Memory storage location specified by the P Register 24.

STF

Consider now the execution of an STF command with reference to its timing diagram FIGURE 23 and to the logic diagram FIGURE 29. When the STF command word operation code portion is in the I Register 23, the DSTF signal, as well as the DFLD signal, becomes "one." Following a normal Sequence Control State 1 and assuming that the STF command is not index modified, Sequence Control State 4 is entered. During the whole of Sequence Control State 4, Memory is addressed from the I Register 23 because the MAMI signal is "one." When the word stored in the specified Memory storage location is available from the Memory Data Register 33, it is gated to the B Register 25 by the BDOB signal.

During execution of an STF command, the influence of the Q Register 22 bit position 00 flip-flop on the A and B inputs to the "F" Full Adder is the reverse of that described above for the LDF command. The DSTF signal is one input to an OR gate G536 so that when the STF command is decoded, G536 is enabled, and its output signal is applied as one input to an AND gate G529. The other input to G529 is driven from the "one" output of the Q Register 22 bit position 00 flip-flop. Thus, whenever the Q Register 22 is right shifted during Sequence Control State 4 of the execution of an STF command, G529 will be enabled or disabled according to whether the information temporarily held in the Q00 Flip-flop is a "one" or a "zero." The output signal from G529 is applied as one input to the OR gate G530. The output signal from G530 thus reflects directly the state of the Q00 Flip-flop during the execution of the STF command. As previously described for the LDF command, the output signal from G530 controls the shifting of the A Register 21 information through the NAND gate G516 to the A input of the "F" Full Adder 27.

The DSTF signal also enables one input to another AND gate G521. The remaining input to G521 is from the "zero" output of the Q Register 22 bit position 00 flip-flop. Therefore, whenever the Q Register 22 is right shifted during Sequence Control State 4 of the execution of an STF command, G521 will be enabled or disabled

according to whether the information temporarily held in the Q00 Flip-flop is a "zero" or a "one." The output signal from G521 is one input to the OR gate G522. As previously described for the LDF command, the output signal from G522 controls the shifting of the B Register 25 information through the NAND gate G517 to the B input of the "F" Full Adder 27. The OR gate G539 is enabled by the DSTF signal, but in all other respects, the shifting of the B Register 25 information to the designated input of the NAND gate G517 is as described for the LDF command.

It is apparent from the above description that the state of the Q00 Flip-flop causes a toggling action partially enabling either the NAND gate G516 or the NAND gate G517 so that either the A Register 21 bit position 00 flip-flop or the B Register 25 bit position 00 flip-flop "one" output is effectively inverted and impressed on the A or B input to the "F" Full Adder 27.

As noted above in the description of the LDF command, the "F" Carry Flip-flop 27A is cleared by the trailing edge of the SC1A signal applied through the OR gate G526 and no carry can result for any one of the 24_{10} shifts during the execution of the STF command because only the "F" Full Adder 27A or B input, but not both, will be enabled if the appropriate register contains a "one" in its lowest order bit.

The information which appears at the S and $\bar{S}$ outputs from the "F" Full Adder 27 is gated serially into the B Register 25 as described above for the LDF command.

30 The word contained within the B Register 25 after the 24th FSRF pulse will be the updated information word to be stored into the Memory storage location specified by the operand address portion of the STF command.

When the A Register 21 is right shifted during the execution of the STF command, it is also circular shifted so that after the final FSRF pulse, the A Register 21 information will be unchanged. The DSTF signal enables an OR gate G537, and the "one" output from G537 enables one input to a NAND gate G538. The other input to the NAND gate G538 is driven by the "one" output from the A Register 21 bit position 00 flip-flop. The output signal from the NAND gate G538 is applied to the A input of the "N" Full Adder 29 so that the S and $\bar{S}$ outputs from the "N" Full Adder 29 reflect the state of the A00 Flip-flop for each shift. The S and $\bar{S}$ outputs from the "N" Full Adder 29 are applied as one input to the OR gates G535 and G534 respectively, and, as previously described for the LDF command, the output signals from G535 and G534 control the information shifted into the A Register 21 bit position 23 flip-flop through the AND gates G512 and G513.

At the trailing edge of the TLPS signal of Sequence Control State 4 of the execution of the STF command, Sequence Control State 5 is entered to store the modified information word which was shifted into the B Register 25 during Sequence Control State 4 into the Memory storage location specified by the operand address portion of the STF command word temporarily stored in the I Register 23. The MAMI signal remains "one" throughout Sequence Control State 5 so that Memory is again addressed from the I Register 23. As shown in the STF timing diagram, FIGURE 23, the signal DBDR becomes "one" during a portion of TCTS time of Sequence Control State 5 to gate the B Register 25 contents to the Memory Data Register 33.

At the trailing edge of the TLPS signal of Sequence Control State 5 of the execution of an STF command, Sequence Control State 1 is reentered to fetch the next command word to be executed from the Memory storage location specified by the P Register 24.

AFA

Consider now the execution of an AFA command with reference to its timing diagram FIGURE 24 and to the logic diagram FIGURE 29. When the AFA command

word operation code portion is in the I Register 23, the DAFA signal, as well as the DFLD signal, becomes "one." Following a normal Sequence Control State 1 and assuming that the AFA command is not index modified, Sequence Control State 4 is entered. During the whole of Sequence Control State 4, Memory is addressed from the I Register 23 because the MAMI signal is "one." When the word stored in the specified Memory storage location is available from the Memory Data Register 33, it is gated to the B Register 25 by the BDOB signal.

The DAFA signal enables both the OR gates G519 and G536 such that either the AND gate G528 or the AND gate K529 must be enabled as the Q Register 22 is shifted right during execution of the AFA command. Since a "one" output signal from either G528 or G529 will enable the OR gate G530, the output signal will remain "one" to constantly enable one input to the NAND gate G516. Thus, as the A Register 21 is right shifted, the "one" output from the A00 Flip-flop is effectively inverted by the NAND gate G516 and applied to the A input of the "F" Full Adder 27.

The DAFA signal enables the OR gate G539, but in all other respects, the shifting of the B Register 25 information to the designated input of the NAND gate G517 is as described for the LDF command.

As previously explained, the "F" Carry Flip-flop 27A is always cleared by the trailing edge of the SC1A pulse applied to the clear input through the OR gate G526. It will be observed however, that, unlike the toggling action which occurs during the execution of the LDF and STF commands, both the A and B inputs to the "F" Full Adder 27 can be enabled simultaneously and carry can result. If a carry does result, the C output from the "F" Full Adder 27 becomes "one" to enable one input to an AND gate G524. The other inputs to G524 are the shift signal FSF and the "one" output signal from the Q Register 22 bit position 00 flip-flop. The $\bar{C}$ output from the "F" Full Adder 27 drives one input to another AND gate G525 which also has the FSF signal and Q00 "one" output signal as inputs.

The output signals from G524 and G525 are input to the OR gates G527 and G526, respectively. G527 and G526 drive the set and clear inputs of the "F" Carry Flip-flop 27A. The "one" output from the "F" Carry Flip-flop 27A is one input to a NAND gate G518 which has as its other input the "one" output signal from the Q00 Flip-flop. Thus, a normal carry will be propagated if the Q00 Flip-flop is set for any one of the FSF pulses.

However, the carries must be limited to the fields defined by the Q Register 22 information. To achieve this control, the DAFA signal is applied to one input to an AND gate G544 which has the FSF signal and the Q Register 22 bit position 00 flip-flop "zero" output signal as its other inputs. When Q00 contains a "zero" during execution of the AFA command, G544 is enabled when an FSF pulse becomes "one." The output signal from G544 is one input to the OR gate G526 which drives the clear input to the "F" Carry Flip-flop 27A. Thus, when the end of a defined field is detected, the "F" Carry Flip-flop 27A is cleared and remains so until another carry results.

The DAFA signal is an input to the OR gate G531 which permits shifting the S and $\bar{S}$ information from the "F" Full Adder 27 into the A Register 21 as described in detail above for the LDF command.

At the trailing edge of the TLPS signal of Sequence Control State 4 of the execution of an AFA command, Sequence Control State 1 is reentered to fetch the next command word to be executed from the Memory storage location specified by the P Register 24.

SFA

Consider now the execution of an SFA command with reference to its timing diagram FIGURE 25 and to the logic diagram FIGURE 29. When the SFA command

word operation code portion is in the I Register 23, the DSFA signal, as well as the DFLD signal, becomes "one." Following a normal Sequence Control State 1 and assuming that the SFA command is not index modified, Sequence Control State 4 is entered. During the whole of Sequence Control State 4, Memory is addressed from the I Register 23 because the MAMI signal is "one." When the word stored in the specified Memory storage location is available from the Memory Data Register 33, it is gated to the B Register 25 by the BDOB signal.

As mentioned briefly above, the subtraction to be effected within each defined field during the execution of an SFA command is brought about by adding the two's complement of the stored field to the corresponding field in the A Register 21. To form the two's complement of a binary number of any length, all "ones" are made "zeros," all "zeros" are made "ones," and an additional count of one is added to the resulting number. The inversion of the "ones" and "zeros" is brought about, during the execution of the SFA command, by activating the NAND gate G517 from the "zeros" output of the B Register 25 bit position 00 flip-flop rather than the "one" output as for the LDF, STF, and AFA commands described above.

The DSFA signal is one input to an OR gate G542. When the DSFA signal is "one," the "one" output from G542 enables one input to an AND gate G543. The other input to G543 is from the "zero" output of the B Register 25 bit position 00 flip-flop so that the output signal from G543 reflects inversely the information in the B00 Flip-flop for each shift during the execution of the SFA command. The output signal from G543 is one input to the OR gate G541, and the output from G541 drives one input to the NAND gate G517 as previously described for the LDF command. Thus, the NAND gate G517 will be fully enabled when Q00 contains a "one" and B00 contains a "zero" to enable the B input to the "F" Full Adder.

The "F" Carry Flip-flop 27A is preset for each defined field to add the necessary additional count of one to develop the two's complement of each B Register 25 field. The DSFA signal is one input to an OR gate G545. When the DSFA signal is "one," the "one" output from G545 enables one input to an AND gate G523 which has the timing signals SC4A and TCT3 as its remaining inputs. The output from G523 is one input to the OR gate G527 which drives the set input to the "F" Carry Flip-flop 27A. Thus, during the execution of the SFA command, G523 will be enabled and the "F" Carry Flip-flop 27A preset before the FSF pulse train arises and the first defined field is operated upon.

The DSFA signal also enables the OR gates G519 and G536 to permit shifting the A Register 21 information to the A input of the "F" Full Adder 27 through the NAND gate G516 as explained in detail above for the AFA command. The DSFA signal also enables the OR gate G531 to permit shifting the difference information from the S and $\bar{S}$ outputs from the "F" Full Adder 27 to the A Register 21 as described in detail above for the LDF command.

The output signal from the OR gate G545 which is enabled by the DSFA signal, is one input to an AND gate G546 which has the FSF signal and the Q Register 22 bit position 00 flip-flop "zero" output as its remaining inputs. The output from G546 is also an input to the OR gate G527 which drives the set input to the "F" Carry Flip-flop 27A. Thus, when the Q Register 22 bit position 00 flip-flop contains a "zero," the trailing edge of an FSF pulse will preset the "F" Carry Flip-flop 27A in preparation for the next defined field to be shifted through the "F" Full Adder 27. The "zero" in Q00 will indicate the end of a field. Any "zero" in Q00 controls carry propagation by disabling the NAND gate G518 as explained for the LDF command above.

At the trailing edge of the TLPS signal for Sequence Control State 4 of the execution of an SFA command, Sequence Control State 1 is reentered to fetch the next command word to be executed from the Memory storage location specified by the P Register 24.

TFL

Consider now the execution of a TFL command with reference to its timing diagram FIGURE 29. When the TFL command word operation code portion is in the I Register 23, the DTFL signal, as well as the DFLD signal, become "one." Following a normal Sequence Control State 1 and assuming that the TFL command is not index modified, Sequence Control State 4 is entered. During the whole of Sequence Control State 4, Memory is addressed from the I Register 23 because the MAMI signal is "one." When the word stored in the specified Memory storage location is available from the Memory Data Register 33, it is gated to the B Register 25 by the BDOB signal.

The DTFL signal enables the OR gates G519, G536, G542, and G545 so that the information shifted to the A, B, and P inputs to the "F" Full Adder 27 is developed in the same manner described in detail above for the SFA command. The DTFL signal is also one input to the OR gate G537 so that the A Register 21 information is circular shifted as described for the STF command and is therefore, effectively unchanged by execution of a TFL command.

The DTFL signal is one input to an AND gate G554 which has the Timing signals TCT3 and SC4A as its remaining inputs. The output signal from G554 is one input to an OR gate G556 which drives the clear input to the Test Flip-flop 69. The Test Flip-flop 69 is therefore cleared at the trailing edge of TCT3 during Sequence Control State 4 of the TFL command before the FSRF pulse train arises.

An AND gate G551 has as inputs the SC4A, DTFL, and FSRF signals, the "one" output from the Q Register 22 bit position 00 flip-flop, the $\bar{C}$ output from the "F" Full Adder 27, and the output from an OR gate G550. The output from G551 is one input to an OR gate G552 which drives the set input to the Test Flip-flop 69. The input signals to the OR gate G550 are TC27, which will coincide with the next to last FSRF pulse, and the "zero" output from the Q Register bit position 01 flip-flop. The function of the OR gate G550 is to detect the end of each field when the last bit of the field is in the Q00 flip-flop.

Each time the end of a field is detected, the AND gate G551 will be enabled with the FSRF signal if the $\bar{C}$ output from the "F" Full Adder 27 is "one." This condition will occur only if no carry is propagated on the last shift of the field under test, and the lack of a carry indicates that the field in the A Register 21 must be less than the corresponding field in the B Register 25. If any field is less and G551 is enabled, the trailing edge of the contemporaneous FSRF signal will disable G551 which will be reflected in the output signal from the OR gate G552 to set the Test Flip-flop 69. Once set, the Test Flip-flop 69 will remain set for the remainder of the TFL command so that it can subsequently be tested by executing a command for that specific purpose.

At the trailing edge of the TLPS signal for Sequence Control State 4 of the execution of the TFL command, Sequence Control State 1 is reentered to fetch the next command word to be executed from the Memory storage location specified by the P Register 24.

TFE

Consider finally the execution of a TFE command with reference to its timing diagram FIGURE 27 and to the logic diagram FIGURE 29. When the TFE command word operation code portion is in the I Register 23, the DTTE signal, as well as the DFLD signal, becomes "one." Following a normal Sequence Control State 1 and assuming that the TFE command is not index

modified, Sequence Control State 4 is entered. During the whole of Sequence Control State 4, Memory is addressed from the I Register 23 because the MAMI signal is "one." When the word stored in the specified Memory storage location is available from the Memory Data Register 33, it is gated to the B Register 25 by the BDOB signal.

The DTTE signal enables the OR gates G519, G536, G542, and G545 so that the information shifted to the A, B, and P inputs to the "F" Full Adder 27 is developed in the same manner described in detail for the SFA command above. The DTTE signal is also one input to the OR gate G537 so that the A Register 21 information is circular shifted as described for the STF command and so is effectively unchanged by execution of a TFE command.

The DTTE signal is one input to an AND gate G533 which has the timing signals TCT3 and SC4A as its remaining inputs. The output signal from G533 is one input to an OR gate G552 which drives the set input to the Test Flip-flop 69. G533 and G552 are enabled and the Test Flip-flop 69 is therefore set at the trailing edge of TCT3 during Sequence Control State 4 of the TFE command before the FSRF pulse train arises.

An AND gate G555 has as inputs the SC4A, DTTE, and FSRF signals, the "one" output from the Q Register 22 bit position 00 flip-flop, and the S output from the "F" Full Adder 27. If, for any shift of the A Register 21 information into the A input of the "F" Full Adder 27 and the inverted information from the corresponding bit position of the B Register 25 to the B input of the "F" Full Adder 27, a "one" signal is obtained from the S output from the "F" Full Adder 27, an inequality will have been detected. If Q00 is a "one" indicating a defined field, the AND gate G555 will be enabled, and its output signal will enable the OR gate G556. At the trailing edge of the contemporaneous FSRF pulse, G555 and G556 will be disabled and the Test Flip-flop 69 cleared. If no inequalities are found, the Test Flip-flop 69 remains set. As noted for the TFL command above, the state of the Test Flip-flop 69 can subsequently be tested by executing a command for that specific purpose.

At the trailing edge of TLPS for Sequential Control State 4 of the execution of the TFE command, Sequence Control State 1 is reentered to fetch the next command word to be executed from the Memory storage location specified by the P Register 24.

What is claimed is:

1. An information processing system including: a first binary register; means responsive to predetermined signals decoded from a word temporarily stored in said first binary register to generate a signal; second, third, and fourth binary registers; a full adder; means responsive to said signal for serially shifting said second, third, and fourth binary registers in synchronism; means responsive to said signal and to a first state of a terminal order bistable device of said second binary register for gating the information represented by the state of a first terminal order bistable device of said third register to a first input of said full adder; means responsive to said signal and to a second state of said terminal order bistable device of said second binary register for gating the information represented by the state of a terminal order bistable device of said fourth binary register to a second input of said full adder; and gating means responsive to said signal for shifting output signals from said full adder serially into a second terminal order bistable device of said third binary register.

2. An information processing system including: a first binary register; means responsive to predetermined signals decoded from a word temporarily stored in said first binary register to generate a signal; second, third, and fourth binary registers; a full adder; means responsive to said signal for serially shifting said second, third, and fourth binary registers in synchronism; means responsive

to said signal and to a first state of a terminal order bistable device of said second binary register for gating the information represented by the state of terminal order bistable device of said third register to a first input of said full adder; means responsive to said signal and to a second state of said terminal order bistable device of said second binary register for gating the information represented by the state of a first terminal order bistable device of said forth binary register to a second input of said full adder; and gating means responsive to said signal for shifting output signals from said full adder serially into a second terminal order bistable device of said fourth binary register.

3. An information processing system including: a first register comprising a plurality of bistable devices for temporarily storing the command word of an instruction to be executed by said information processing system; means responsive to a predetermined configuration of a command word temporarily stored in said first register to generate a signal; second, third, and fourth registers, each of said second, third, and fourth registers comprising a plurality of bistable devices representing successive orders of significance; a full adder; means responsive to said signal for serially shifting said second, third, and fourth registers in synchronism; means responsive to said signal and to a first state of the lowest order bistable device of said second register for gating the information represented by the state of the lowest order bistable device of said third register to a first input of said full adder; means responsive to said signal and to a second state of the lowest order bistable device of said second register for gating the information represented by the state of the lowest order bistable device of said fourth register to a second input of said full adder; and gating means responsive to said signal for serially shifting output signals from said full adder serially into the highest order bistable device of said third register.

4. An information processing system as recited in claim 3 including circular shifting means for said second register adapted to function in synchronism with the serial shifting of said second, third, and fourth registers.

5. An information processing system including: a first register comprising a plurality of bistable devices for temporarily storing the command word of an instruction to be executed by said information processing system; means responsible to a predetermined configuration of a command word temporarily stored in said first register to generate a signal; second, third, and fourth registers, each of said second, third, and fourth registers comprising a plurality of bistable devices representing successive orders of significance; a full adder; means responsive to said signal for serially shifting said second, third, and fourth registers in synchronism; means responsive to said signal and to a first state of the lowest order bistable device of said second register for gating the information represented by the state of the lowest order bistable device of said third register to a first input of said full adder; means responsive to said signal and to a second state of the lowest order bistable device of said second register for gating the information represented by the state of the lowest order bistable device of said fourth register to a second input of said full adder; and gating means responsive to said signal for serially shifting output signals from said full adder serially into the highest order bistable device of said fourth register.

6. An information processing system as recited in claim 5 including first circular shifting means for said second circular shifting means for said third register, each of said first and second shifting means adapted to function in synchronism with the serial shifting of said second, third, and fourth registers.

7. An information processing system including: a first register comprising a plurality of bistable devices for temporarily storing the command word of an instruction to be executed by said information processing system;

means responsive to a predetermined configuration of a command word temporarily stored in said first register to generate a signal; second, third and fourth registers, each of said second, third, and fourth registers comprising a plurality of bistable devices representing successive orders to significance; a full adder; first means responsive to said signal for serially shifting said second, third, and fourth registers in synchronism; second means responsive to said signal for gating the information represented by the state of the lowest order bistable device of said third register to a first input of said full adder; means responsive to said signal and to a first state of the lowest order bistable device of said second register for gating the information represented by the state of the lowest order bistable device of said fourth register to a second input of said full adder; third means responsive to said signal for serially shifting output signals from said full adder serially into the highest order bistable device of said third register; a carry bistable device responsive to carry output signals from said full adder to enter a predetermined state according to the states of the carry output signals; means responsive to a first state of the lowest order bistable device of said second register for gating the carry information represented by the state of said carry bistable device to a third input of said full adder; and means responsive to said signal and to a second state of the lowest order bistable device of said second register to place said carry bistable device into a predetermined state.

8. An information processing system as recited in claim
30 7 including circular shifting means for said second register
adapted to function in synchronism with the serial shift-
ing of said second, third, and fourth registers.

35 9. An information processing system including: a first register comprising a plurality of bistable devices for temporarily storing the command word of an instruction to be executed by said information processing system; means responsive to a predetermined configuration of a command word temporarily stored in said first register to generate a signal; second, third, and fourth registers, each of said second, third, and fourth registers comprising a plurality of bistable devices representing successive orders of significance; a full adder; first means responsive to said signal for serially shifting said second, third, and fourth registers in synchronism; second means responsive to said signal for 40 gating the information represented by the state of the lowest order bistable device of said third register to a first input of said full adder; means responsive to said signal and to a first state of the lowest order bistable device of said second register for gating the complement of the information represented by the state of the lowest order bistable device of said fourth register to a second input of said full adder; third means responsive to said signal for serially shifting output signals from said full adder serially into the highest order bistable device of said third register; 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875

65 10. An information processing system as recited in claim 9 including circular shifting means for said second register adapted to function in synchronism with the serial shifting of said second, third, and fourth registers.

11. An information processing system including: a first register comprising a plurality of bistable devices for temporarily storing the command word of an instruction to be executed by said information processing system; means responsive to a predetermined configuration of a command word temporarily stored in said first register to generate a signal; second, third, and fourth registers, each of

said second, third, and fourth registers comprising a plurality of bistable devices representing successive orders of significance; a full adder; first means responsive to said signal for serially shifting said second, third, and fourth registers in synchronism; second means responsive to said signal for gating the information represented by the state of the lowest order bistable device of said third register to a first input of said full adder; means responsive to said signal and to a first state of the lowest order bistable device of said second register for gating the complement of the information represented by the state of the lowest order bistable device of said fourth register to a second input of said full adder; a carry bistable device responsive to carry output signals from said full adder to enter a predetermined state according to the states of the carry output signals; means responsive to a first state of the lowest order bistable device of said second register for gating the carry information represented by the state of said carry bistable device to a third input of said full adder, and means responsive to said signal and to a second state of the lowest order bistable device of said second register to place said carry bistable device into a predetermined state; a test bistable device; fourth means responsive to said signal for presetting said test bistable device into a predetermined first state; and means responsive to said signal, to a first state of the lowest order bistable device of said second register, and to the carry signals from said full adder to switch said test bistable device into a second state.

12. An information processing system as recited in claim 11 including first circular shifting means for said second register and second circular shifting means for said third register, each of said first and second shifting means adapted to function in synchronism with the serial shifting of said second, third, and fourth registers.

13. An information processing system including: a first register comprising a plurality of bistable devices for temporarily storing the command word of an instruction to be executed by said information processing system; means responsive to a predetermined configuration of a command word temporarily stored in said first register to generate a signal; second, third, and fourth registers, each of said second, third, and fourth registers comprising a plurality of bistable devices representing successive orders of significance; a full adder; first means responsive to said signal for serially shifting said second, third, and fourth registers

in synchronism; second means responsive to said signal for gating the information represented by the state of the lowest order bistable device of said third register to a first input of said full adder; means responsive to said signal and to a first state of the lowest order bistable device of said second register for gating the information represented by the state of the lowest order bistable device of said fourth register to a second input of said full adder; a carry bistable device responsive to carry output signals from said full adder to enter a predetermined state according to the states of the carry output signals; means responsive to a first state of the lowest order bistable device of said second register for gating the carry information represented by the state of said carry bistable device to a third input of said full adder; and means responsive to said signal and to a second state of the lowest order bistable device of said second register to place said carry bistable device into a predetermined state; a test bistable device; fourth means responsive to said signal for presetting said test bistable device into a predetermined first state; and means responsive to said signal, to a first state of the lowest order bistable device of said second register, and to the sum signals from said full adder to switch said test bistable device into a second state.

14. An information processing system as recited in claim 13 including first circular shifting means for said second register and second circular shifting means for said third register, each of said first and second circular shifting means adapted to function in synchronism with the serial shifting of said second, third, and fourth registers.
